Design for Cotton Mill, stores
Patented Oct. 20, 1855

Des. 693

S. W. Gibbs, of Albany N.Y. Assign to
North, Chase & North, of Philadelphia, Pa.
Sellers Patent No 693. Dated Feb 20, 1855.

The schedule referred to in their Letter Patent and making part of the same.

To all whom it may concern:— Be it known that S. W. Gibbs, of the City

215
H. H. Gibbs

and County of Albany, and State of New York, have invented a new and improved design for cooking stoves; and I do hereby declare that the following is a full and exact description thereof, reference being had to the accompanying drawings, making part of this specification, in which:

Fig. 1. represents a side profile; Fig. 2. represents a front fire door; Fig. 3. represents a foot. a, a, a, a, a, a, are mouldings; b, b, b, b, b, b, b, are ornamental flatings.

What I claim as my invention and desire to secure by a Letters Patent, is the design and configuration of the ornamental flatings and mouldings herein described forming an ornamental design for cooking stoves.
